SUPPLY OF MATERIAL IN WRAPPING MACHINES

John Crighton, London, England, assignor to
 American Machine & Foundry Company, New
 York, N. Y., a corporation of New Jersey

Application November 18, 1936, Serial No. 111,423
 In Great Britain November 20, 1935

21 Claims. (Cl. 164—49)

This invention relates to the supply of wrapping material in wrapping machines of the type wherein the wrapping material is in web form and is fed to severing mechanism by which wrap-
 per lengths are severed.

In connection with cigarette wrapping or packing machines in which the bundles of cigarettes are wrapped in foil it has been the practice hitherto to stop the machine in the event of a
 10 breakage of the web or when the supply reel runs out and an object of the present invention is to provide an improved feed for the wrapping web whereby such stoppages are rendered unnecessary.
 15 The invention consists in means for feeding wrapping or like material in web form to severing means, wherein a spare supply of the material is provided, and means are provided set in operation by the breakage or exhaustion of the
 20 running web whereby the spare web is automatically delivered to the web feeding means.

The feeding of the material to the severing means may be effected by main feeding rolls while the delivery of the spare web to the main
 25 feed rolls may be effected by auxiliary feed rolls preferably comprising an idle roll for each web adapted, on a fault occurring in the running web, to be moved into engagement with the main feed rolls.

30 The change over to the spare web may be effected by electrically operated means which function upon the breakage or exhaustion of the running web.

The webs may pass through detector mecha-
 35 nism controlling said electrically operated means.

The invention is particularly adapted to the supply of wrapping foil in cigarette wrapping machines, and the invention will be described in such connection, but it may be applied to other
 40 machines where sections of wrapping material are adapted to be severed from a running web such as cork tipping-machines.

In the accompanying drawings which illustrate the invention as applied to a foil supplying mech-
 45 anism for cigarette packing machines:

Figure 1 is a front elevation of the mechanism with certain parts removed for clearness;

Figure 2 is a side elevation partly in section;

Figure 3 is a front elevation of controlling
 50 mechanism which is located in front of the parts shown in Figure 1;

Figure 4 is a side view corresponding to Figure 3;

Figure 5 is a plan of auxiliary feed rolls;

55 Figure 6 is a plan of the severing knives;

Figure 7 is a detail of deflecting means;
 Figure 8 is a diagrammatic representation of the cams.

In carrying the invention into effect according to one convenient mode a pair of supply reels 5
 10 11 is provided which are located on spaced horizontal spindles 12, 13 carried by brackets 14,
 15 the webs being drawn off downwardly to feeding and severing mechanism.

The feeding mechanism comprises a pair of 10
 feed rolls 16, 17 located on horizontal axes and of which 16 is intermittently driven by suitable means. The roll 17 is free to rotate and is spring pressed towards the other roll, the trunnions of the roll 17 being carried in sliding bearings 18. 15

The tension of the spring 19 and thus the pressure of the roll 17 may be adjusted by the screw 20. A rotary cam 21 co-operating with a flange 22 on the adjusting screw 20 is provided for opening the feed rolls when necessary. 20

The intermittent drive to the feed roll 16 is effected by a Geneva drive comprising a slotted disc 23 and a driving disc 24 having a driving roller 25. The drive from the disc 23 is through gearing 26, 27. 25

During the stationary non-feeding periods of the feed rolls 16, 17 the disc is locked by the roll 28 carried by the lever 29 which is controlled by the rotary cam 30 which is conveniently formed on the edge of the disc 24. 30

Below the feed rolls 16, 17 severing means are provided which may be of any suitable type, for example a reciprocating cutting knife 31 may co-operate with a fixed knife or ledger plate 32. The reciprocating knife 31 is mounted in guides 33 (see Figure 6) and is cam operated from the cam 34 which engages a roll 35 on the lever 36 mounted upon the rock shaft 37 to which the mounting for the knife 31 is connected. 35

The cam 34 is mounted upon the spindle 38 40 which also carries the driving disc 24 and cam 30. The spindle 38 is constantly driven from any suitable source.

Above the main feed rolls, auxiliary feed rolls 49, 51 are provided one for each web. The auxiliary feed rolls are mounted for free rotation on spindles carried by frames 42 pivoted at 42x upon levers 43 (see Figs. 1 and 5). Normally the auxiliary feed rolls 49, 51 are spaced from the main feed rolls 16 and 17 so that there is no drive 50 upon the web from the auxiliary feed rolls, but on swinging the levers 43 downwardly the auxiliary rolls are brought into a position to press the webs on to the main feed rolls in a manner hereinafter referred to. 55

The frames 42 are freely pivoted on the levers 43 so that equal pressure will be exerted by the rolls 40, 41 when they come into operation.

Between the auxiliary feed rolls 40, 41 and the supply rolls 10 and 11, a detector mechanism is provided comprising a pair of rolls 44, 45 which form contact elements in an electrical circuit. Normally the circuit is broken by the presence of the web but when the web breaks or is exhausted contact is made between the rolls to complete the circuit. In the case of a foil wrapping for cigarettes it will be appreciated that the foil is backed by thin paper which breaks the circuit.

15 The inner detector rolls 45 are carried by pivoted levers 46 which are connected at their free ends by a spring 47 so that the rolls are spread apart to engage the complementary rolls 44 (or the webs as the case may be).

20 The upper ends of the levers 46 are also connected to the toggle links 48, the middle joint of the links being connected to a sliding block 49 which carries a spring pressed pawl 50.

One of the levers 43 carrying the movable auxiliary feed rolls is provided with a roller 51 engaging a bracket 52 on a vertically slidable control bar 53 mounted forwardly of the feed rolls 16 and 17. The bar 53 is normally maintained in its upper position whereby the auxiliary feed rolls 30 are held in their raised or inoperative position.

The control bar 53 which is formed in two parts connected by a threaded rod 54 for purposes of lengthwise adjustment, is held in its upper position by a solenoid 55 which is in circuit with the detector rolls 44, 45. The core 56 has a tongue 57 which normally underlies a projection 58 on the control bar. A bracket 59, Figure 3, supports the core. When the projection 58 is in engagement with the tongue 57 there is sufficient friction, or the gripping effect between the projection 58 and bracket 59 is such that the core is prevented from moving to its release position, even though the coil is energised.

In order to permit the release of the tongue, 45 the control bar 53 is raised during each cycle of operation by means of a rotary cam 60, engaging a roll 63 on a pivoted lever 62 the end of which lever 62 underlies a roll 64 on the lower end of the bar 53.

50 The cam 60 is shaped so that it will lift the bar 53 slightly each rotation to free the tongue 57 so that in the event that the coil of the solenoid has been energised the core will be withdrawn. The rotations of cam 60 are synchronised with 55 the feed rollers so that the period during which the tongue 57 is free to be withdrawn overlaps a portion of the feed and a portion of the stationary period of the feed rolls.

It will be appreciated that when a detection 60 occurs at either of the pairs of detector rolls, there will be a length of web between the knife and the roll and in order that such length shall be used before the solenoid operates, it is preferred to provide an interrupter in the solenoid 65 circuit which may comprise a rotary device having a contact strip adapted to give a 90° contact. The interrupter is synchronised with the feed roll so the circuit will be made (assuming of course that a detection has occurred at the rolls 70 44, 45) immediately the feed roll completes its feed.

In order to get rid of the short end piece of the web which will be fed by the rolls after a detection, a web diverting device is provided below the knife. This diverter comprises a trans-

verse plate 64x mounted upon a pivoted support 65. The support is provided with a projection 66 (Fig. 3) which lies in the path of a rod 67 adjustably mounted on the control bar 53. A spring 68 is provided to retain the support 65 against a stop 69 and thus hold the diverter plate 64x in the inoperative position.

When the control bar 53 descends, the rod 67 swings the support to bring the diverter plate into the diverting position see Figure 7, in which it is 10 held by the projection 66 engaging the lower side of a pivoted catch 70. The catch 70 has a nose 70a which engages the upper end of a slidable resetting bar 71 and is retained against such bar by a spring 72 (Fig. 3).

The resetting bar 71 engages at its lower end, a pivoted lever 73 having a roll 74 adapted for engagement by a cam 75 fixed on the side of the cam 60.

When the cam 75 swings the lever 73, the resetting bar is raised and turns the catch 70 anti-clockwise. This causes a clockwise rotation of the diverter support 65 and thus swings the diverter plate 64x from its diverting position to the right and positively ejects the piece of web. 20 On further movement the catch slips past the end of projection 66 and allows the support 65 to return under the action of the spring 68 whereby the diverter plate is returned to its normal position.

30 Adjacent its upper end the control bar 53 is provided with an adjustable detent 76 which when the bar moves downwardly after a detection moves past the pawl 50 which is returned by its spring to lie in the path of the detent. On the control bar being raised by the cam 60 the detent 35 engages the pawl and lifts the sliding block 49 which through the toggle levers 48 (Fig. 1) swings the levers 46 and thus moves the detector rolls 45 inwardly out of engagement with the rolls 44 and 40 thus breaks the circuit of the solenoid 55 whereby the core 56 is free to return and support the control bar.

The resetting of the detector rolls 45, after a rethreading of the broken web, or replenishment 45 of an exhausted web, is effected manually by the operator. This is effected by pressing on the button 77 (Fig. 1) which brings the coned pin 78 into engagement with the upper end of the pawl 50 causing the pawl to turn anti-clockwise as seen in Figure 2 whereby the pawl is turned anti-clockwise out of the path of the detent 76, and at the same time the toggle is broken and the spring 47 placed under tension which draws the arms 46 together and biases the detector rolls 45 apart into the position shown in Fig. 1. Upon release of the button 77, the pawl assumes its normal position, as shown in Fig. 4, ready to be lifted upon the next upward movement of the detent 76 when the control bar 53 is raised.

60 The relative setting of the cam 34 controlling the knife, the change over cam 60 for the control bar 53, and the cam 75 controlling the foil deflector with regard to the web feed rolls is shown in developed form in Figure 8 in which the upper line a represents the drive to the main feed rolls, line b represents the cam 34, line c the cam 60 and line d the cam 75.

In operation, assuming that the right hand supply reel is the running web, the web from the left hand reel is brought down through the left hand detector rolls and between the left hand auxiliary feed roll 40 and the driven feed roll 16 until the leading end lies in the bight of the 75

rolls 16 and 17 but such that it cannot be gripped by the main feed rolls 16 and 17.

With this state of affairs the auxiliary feed rolls 40, 41 are held in the raised position by the 5 control bar 53 which is prevented from falling by the tongue 57 of the core of the solenoid.

Now should the right hand web break or become exhausted, contact will be made between the right hand detector rolls 44, 45 and the solenoid 10 circuit closed at this point. The solenoid will not however become energized until the circuit is completed by the interrupter, i. e., at the end of the feeding period of the main feed rolls.

15 The solenoid core will then be free to retract when the cam 60 raises the control bar 53 to disengage the tongue 57 of the core.

The control bar will now fall, allowing the auxiliary feed rolls 40, 41 to be lowered by the 20 spring 43a into driving contact with the main feed rolls so that the left hand standing web will be fed between the main feed rolls.

At the same time the detent 76 on the control bar will move beneath the pawl 50 ready to 25 raise the pawl and open the circuit at the detector rolls when the control bar is reset.

Also when the control bar drops, the rod 67 swings the deflector plate 64x to a position beneath the knives in which the end or scrap piece 30 of web will be deflected, in which position it will be retained by the projection 66 lying beneath the catch 70.

As the cam 60 completes its cycle the control bar 53 is raised so that the solenoid core is free 35 to return, to retain the bar in raised position, the solenoid in the meantime having been de-energized by the interrupter. The raising of the bar 53 opens the detector rolls by the lifting of the sliding block 49, and also raises the auxiliary feed rolls 40, 41.

At the same time the cam 75 lifts the resetting bar 71 causing an ejecting movement of the deflector plate 64x to positively eject the end piece 45 of the web, or as may happen a double thickness 40 of oil, after which the deflector is returned to its normal position.

The parts are now reset for the feeding of the left hand web.

The operator now threads through the broken 50 or replenished right hand web passing it between the right hand detector rolls, beneath the auxiliary feed roll 41 and into the bight between the main feed rolls 16, 17, stopping the leading end of the web so that there is no gripping of the 55 web by the feed rolls.

After the web has been thus threaded in position the detector rolls are reset by the operator pressing the button 77 which allows the pawl 50 to ride past the detent 76 on the control bar.

60 The right hand web is now the standing web and in a fault occurring by a breakage of the left hand web or exhaustion of such web, a detection again occurs and the right hand web is brought into use.

65 The invention is of particular advantage when used with a duplex feed wrapping machine as it avoids the disadvantage hitherto experienced of having to stop both feeds even when only one web had broken or become exhausted.

70 While the invention has been described in connection with wrapping machines it may also be applied in other machines where sections of material are severed from a running web where 75 it is desirable to avoid stoppage of the machine

for breakages or the like; and, for example, it may be applied to cork tipping machines.

I claim:

1. In a wrapping machine of the class described; severing means; and mechanism for feeding wrapping or like material in web form to said severing means, wherein two supply reels are provided, and main feeding means, with two identical sets of auxiliary feeding devices, adapted to be set automatically in operation selectively by the breakage or exhaustion of either web when running, and change-over devices whereby the other web is thereupon automatically delivered to the main web feeding means. 10

2. In a wrapping machine of the class described; severing means; and mechanism for feeding wrapping or like material in web form to said severing means, said feeding mechanism including two supply reels, with a common set of main feeding means, and two identical sets of auxiliary feeding means each adapted to be operated at times and inoperative at other times; duplicate means for detecting a breakage in, or exhaustion of, the running web; and means set in operation by the breakage or exhaustion of the running web to operate the appropriate auxiliary feeding means to deliver the spare web to the main feeding means. 15

3. In a wrapping machine of the class described; severing means; and mechanism for feeding a web of metal foil wrapping or like material to said severing means, said feeding mechanism including two supply reels, with a common set of main feeding means, and two identical sets of auxiliary feed roll devices, one 30 for each web, which rolls are normally inoperative; and means controlled by the breakage or exhaustion of the running web to bring the appropriate auxiliary feed roll devices into operation to deliver the spare web to the main feeding 35 means.

4. In a wrapping machine of the class described; severing means; and mechanism for feeding a web of metal foil wrapping or like material to said severing means, said feeding 45 mechanism including two supply reels, with a common set of main feed rolls, and change-over devices adapted to be set in operation by the breakage or exhaustion of the running web, whereby the spare web is withdrawn from its 50 reel and automatically delivered to the web feeding means, said change-over devices being controlled by electrically operated means.

5. In a wrapping machine of the class described, severing means and mechanism for feeding 55 wrapping or like material in web form to said severing means, as claimed in claim 4, and wherein a detector mechanism is provided to sense a fault in the running web and to control said electrically operated means, the webs being 60 passed through said detector mechanism.

6. Mechanism for feeding wrapping or like material in web form to severing means; comprising a plurality of supply reels; a common set of main feed rolls; uniform sets of auxiliary 65 feed roll devices, one for each web; means to actuate said main feed rolls and said auxiliary feed roll devices; a vertically reciprocable control bar arranged to maintain each of said auxiliary feed roll devices normally in a predetermined 70 control position; a withdrawable element for holding said bar in said last named position, to incapacitate that one of the auxiliary feed roll devices which may be operating in conjunction with the running web; and detector means 75

to withdraw said element and thereby rehabilitate an appropriate auxiliary feed roll device, whereupon the latter is made effective to deliver into the main feed rolls the web controlled by said last-named auxiliary feed roll device.

5. Means for feeding wrapping or like material to severing means as claimed in claim 6, wherein the withdrawable element comprises the core of a solenoid which is in circuit with detector mechanism through which the web passes.

10. Means for feeding wrapping or like material to severing means as claimed in claim 6, wherein the auxiliary feed roll devices are respectively located above the main feed rolls and each is adapted to be lowered onto one of the main feed rolls on detection of a fault in the running web, to feed the standing web.

15. Means for feeding wrapping or like material to severing means as claimed in claim 6, wherein the auxiliary feed roll devices are respectively located above the main feed rolls and each is carried by a spring pressed lever having an abutment cooperating with a projection on said control bar to maintain said incapacitated auxiliary feed roll device out of engagement with the main feed rolls until a fault occurs in the running web.

20. In a wrapping machine of the class described; severing means; and mechanism for feeding wrapping or like material to said severing means as claimed in claim 4, wherein detector mechanism is provided, comprising a pair of rolls for each web, and an electrical circuit in which each pair of rolls is included, said circuit being adapted to be closed through contiguous portions of said rolls in the absence of a web therebetween, and said circuit being opened when the rolls of a pair are maintained out of contact by the presence of a web therebetween; and means in said circuit, and operated by closure thereof, to cause another web to be fed.

25. Mechanism for feeding wrapping or like material in web form to severing means; comprising a plurality of supply reels; a common set of main feed rolls; uniform sets of auxiliary feed roll devices, one for each web; means to actuate said main feed rolls and said auxiliary feed roll devices; a vertically reciprocable control bar, arranged to maintain each of said auxiliary feed roll devices normally in a predetermined control position; a detector mechanism comprising a pair of rolls for each web, and between the rolls of which pair the corresponding web is caused to pass, and an electrical control circuit in which each such pair of rolls is included, said circuit being adapted to be closed through contiguous portions of said rolls in the absence of a web therebetween, and said circuit being opened when the rolls of a pair are maintained out of contact by the presence of a web therebetween; and means in said circuit, and operated by closure thereof, to cause another web to be fed into said main feed rolls; said last-named means including an electromagnetic device responsive to circuit conditions and having a core with a tongue adapted to intersect the path of movement of the control bar, and the core being moved in response to current flow in the solenoid to retract the tongue and permit the control bar to fall, thereby allowing the appropriate auxiliary feed rolls to be engaged with the main feed rolls, so that the said auxiliary feed rolls will feed the standing web between the main feed rolls; each 70 pair of detector rolls having a stationary roll

and a movable roll, the movable rolls being mounted upon levers having spring means for pressing each of such rolls toward the associated stationary roll.

12. Means for feeding wrapping or like material to severing means as claimed in claim 11, wherein each lever is connected to a toggle, the pivot of which is coupled to a slide adapted to be lifted by said vertically reciprocating control bar after a detection to move the movable detector roll away from the stationary detector roll and open the circuit.

13. Means for feeding wrapping or like material to severing means as claimed in claim 11, wherein each lever is connected to a toggle, the pivot of which is coupled to a slide adapted to be lifted by said vertically reciprocating control bar after a detection to move the movable detector roll away from the stationary detector roll and open the circuit of a solenoid, the core of which normally underlies a projection on said bar and is withdrawn on a fault being detected at the detector rolls.

14. Means for feeding wrapping or like material in web form to severing means as claimed in claim 6; and wherein the withdrawable element comprises the core of a solenoid which is in an electrical control circuit with said detector mechanism through which the webs pass, and means to interrupt the solenoid circuit to delay withdrawal of the solenoid core and release of the control bar, after the closing of the circuit by a detection, until released at a predetermined part of a cycle.

15. Mechanism of the class described for feeding wrapping or like material in web form to severing means; said mechanism comprising a plurality of supply reels of the material; intermittently operating main feed rolls; auxiliary feed rolls for each web; a vertically reciprocable control bar adapted to maintain each of said auxiliary feed roll devices selectively in a raised inoperative position; a detector means through which the webs pass; a withdrawable element for supporting said bar in the raised position, said element comprising the core of a solenoid in circuit with said detector means; and means to energize the solenoid on the breakage or exhaustion of the running web to withdraw the solenoid core and allow the bar to fall, and means released by the fall of the bar to effect engagement of the auxiliary feed rolls with the main feed rolls to deliver the spare web to the main feed rolls, and means to interrupt the solenoid circuit to delay withdrawal of the solenoid core, when a detection has occurred, until the end of a feeding period of the main feed rolls.

16. Means for feeding wrapping or like material to severing means as claimed in claim 15, wherein the control bar is formed with a surface which frictionally engages a surface on the core to delay withdrawal of the core and in which a rotary cam is provided to lift the bar and thus to disengage said surfaces, said rotary cam being synchronized with the drive of the main feed rolls.

17. Mechanism of the class described for feeding wrapping or like material in web form to severing means, said mechanism comprising a plurality of supply reels, each adapted to serve in turn as a spare reel; main web-feeding means; auxiliary web-feeding devices; change-over means adapted to make said webs selectively effective; electrically operated means adapted to be set in operation by the breakage or exhaustion of the running web whereby the appropriate aux- 75

- illary web-feeding devices are activated and the spare web is automatically delivered to the main-web-feeding means, said electrically operated means including a pair of detector rolls for each web, through the rolls of which pair the corresponding web passes, one roll of each pair being mounted on a lever having spring means for pressing said roll toward the other roll, said levers being pivotally connected to a toggle, the pivot of which is coupled to a slide adapted to be lifted by a vertically reciprocating control bar after a detection to move the movable rolls away from the other rolls to break the circuit, said slide carrying a pivoted pawl adapted to be engaged by a 10 detent on said bar to raise the slide, said detent riding past the pawl when the control bar drops.
18. Means for feeding wrapping or like material to severing means as claimed in claim 17, wherein a manually operable setting pin is provided mounted to reciprocate to engage the pawl and release it from the detent to permit the movable detector rolls to move outwardly towards the stationary rolls.
19. Means for feeding wrapping or like material to severing means as claimed in claim 6, wherein

a deflecting device is provided which is adapted to be moved to a deflecting position beneath the severing means when the control bar drops after a detection by means carried by the control bar.

20. Means for feeding wrapping or like material to severing means as claimed in claim 6, wherein a deflecting device is provided which is adapted to be moved to a deflecting position beneath the severing means when the control bar drops after a detection by means carried by the control bar and wherein the return of the deflector device is controlled by means which first impart an ejecting movement to the deflector.

21. Means for feeding wrapping or like material to severing means as claimed in claim 6, wherein a pivotally mounted deflector is provided having a returning spring and is adapted to be swung to a deflecting position beneath the severing means by means carried by the control bar and wherein a pivoted pawl is provided for retaining the deflector in the deflecting position and for effecting its release, said pawl first moving the deflector to an ejecting position and being operated by a cam controlled reciprocating bar.

JOHN CRIGHTON. 25
